UNITED STATES PATENT OFFICE.

ASBURY H. HAMILTON, OF BROOKLYN, NEW YORK.

SANITARY CLOTHES-HAMPER.

1,130,509.

Specification of Letters Patent.

Patented Mar. 2, 1915.

Application filed November 26, 1913. Serial No. 803,152.

To all whom it may concern:

Be it known that I, ASBURY H. HAMILTON, a citizen of the United States, residing at Brooklyn, in the county of Kings and State of New York, have invented new and useful Improvements in Sanitary Clothes-Hampers, of which the following is a specification.

The present invention has reference to 10 linen hampers, and it proposes, briefly, an improved receptacle of the general character specified which is so constructed as to provide for the passage of air into and through its contents, whereby it may be 15 utilized with equal facility either for the storage of clean linen, or as a repository for soiled linen, and, therefore, commends itself, by reason of its sanitary properties or qualities, for use in both hospitals and 20 private residences.

More especially, the invention comprehends an improved sanitary hamper comprising a chest or outer case having a portion thereof provided with ventilation openings, and an inner case or receptacle proper 25 which is adapted to directly contain the linen and to be fitted, removably within the outer case, this inner case being constructed either wholly or in part, according to its 30 use, of foraminous material, so that a constant circulation of air through its entire contents is insured.

An embodiment of the invention is illustrated in the accompanying drawing, whereof:—

Figure 1 is a perspective view of the above-mentioned chest or outer case of the hamper, with the lid open, and a portion of the front wall broken away; Figs. 2 and 40 3 are perspective views of the two forms or styles of inner case; and Figs. 4 and 5 are fragmental, longitudinal vertical sectional views showing the cases depicted in Figs. 2 and 3, respectively, disposed within 45 the chest or outer case and the lid of the latter closed.

In said drawing, 1 designates, generally, the aforesaid chest or outer case, and 2 and 3 the two forms or styles of inner case, 50 which latter may be used, either each with a separate outer case, or, if preferred, both with the same case, as will be hereinafter explained.

The chest or outer case 1 may be 55 constructed of any suitable material, and in any desired shape and size. Preferably,

however, it has the form of an elongated, open-topped rectangular box, as shown, and is provided with a hinged or swinging lid or cover 4. It may be readily carried from place to place, and is furnished for this purpose with suitable handles 5, which are attached to its ends 6. To provide for the free entrance of air into its interior, its floor or bottom member 7 is of skeleton or frame-like 65 formation, and is faced or backed with a panel or panels 8 of wire gauze, or like foraminous material, as best shown in Fig. 1, the aforesaid bottom member being supported above the floor or ground, to permit 70 access of air thereto, by means of blocks 9, which, in turn, may be equipped with casters 10.

The inner case, or linen receptacle proper, as previously stated, is designed to be 75 removably fitted within the chest or outer case, and to have either of the forms shown in Figs. 2 and 3, according as it is to receive either clean or soiled linen. In either instance, the inner case is constructed to some 80 extent of wire-gauze or the like, so as to permit the air entering the chest through the gauze panel or panels 8 to pass from all sides into the inner case and through its contents. The case 2, represented in Fig. 2 is 85 intended as a storage receptacle for clean linen, and, therefore, does not require as great a quantity of air to circulate through it, as is needed where the soiled-linen receptacle 3, depicted in Fig. 3 is used. Accordingly, the clean-linen case 2, which is likewise in the form of an elongated, open-topped, rectangular box, is constructed of 90 wooden panels or members, each of which, with the exception of the bottom panel or 95 floor, is formed with a transverse slot 11, of suitable size and shape, faced or covered with a gauze strip or panel 12 through which the air enters the case when the lid of the chest is closed, as indicated by the 100 arrows in Fig. 4. This case is supported above the floor 7 of the said chest or outer case by means of suitable blocks 13, here shown as attached to the closed bottom panel of the case. To facilitate lifting of 105 the case into and out of the chest, the former is provided at its upper edges with a continuous, outwardly-extending flange 14, the end portions of which are furnished with loosely-mounted loop-shaped handles 15.

The soiled linen receptacle or case 3, shown in Fig. 3, is somewhat similar in

shape to the case 2, previously described, but is constructed entirely of wire gauze, and is designed to rest directly upon the floor of the outer case. Like case 2, it is 5 provided with a continuous marginal flange 16 at its top, which flange, in turn, is furnished with swinging handles 17. In use, either of the two inner cases may be conformably fitted in the outer case or chest, 10 and the linen deposited therein, or each of the former cases may be used with a separate outer case or chest, accordingly as may be desired, and in one instance such inner case may act as a permanent storage 15 receptacle, while in the other instance it may be removed, when filled, and transported to the laundry. In both instances, however, the linen in the inner case, whether clean or soiled, is constantly ventilated by 20 the passage of air therethrough, and the lid of the outer case or chest may thus be kept closed without in any way impairing the air circulation, a matter of considerable importance where the hamper is used as a receptacle for soiled linen. Moreover, the 25 ease with which the inner cases may be lifted out of and into the outer case enables the latter to be readily and thoroughly

cleaned, while the construction of the said inner cases themselves is such as to permit 30 them to be cleaned throughout, so that the entire hamper may, therefore, be kept in a perfectly sanitary condition.

What I claim as my invention:—

1. In combination, a portable case having 35 imperforate side and end walls and a bottom provided with a ventilating screened opening, a clothes receptacle adapted to fit in the case and provided with a screen and ventilating wall, and an imperforate cover 40 for the case.

2. In combination, a case having imperforate side walls and a ventilating screened bottom, means for supporting the bottom out of contact with the floor, a receptacle 45 provided with a bottom and side walls of foraminous material and disposed in the case and spaced from the side walls thereof, and an imperforate cover for the case.

In testimony whereof I have hereunto set 50 my hand in presence of two subscribing witnesses.

ASBURY H. HAMILTON.
